UNITED STATES PATENT OFFICE.

JOHN H. MILLER, OF BATAVIA, ILLINOIS, ASSIGNOR TO THE UNITED STATES WIND ENGINE AND PUMP COMPANY, OF SAME PLACE.

WINDMILL-BRAKE.

SPECIFICATION forming part of Letters Patent No. 531,420, dated December 25, 1894.

Application filed September 19, 1894. Serial No. 523,490. (No model.)

To all whom it may concern:

Be it known that I, JOHN H. MILLER, a citizen of the United States, residing at Batavia, in the county of Kane and State of Illinois, have invented a certain new and useful Improvement in Windmill-Brakes, which is fully set forth in the following specification, reference being had to the accompanying drawings, in which—

- o Figure 1 is a side elevation of my invention showing the parts of a windmill to which it is applied. Fig. 2 is a top or plan view of the same. Fig. 3 is a vertical sectional view, taken at the line 3—3, Fig. 1, looking to the right. Fig. 4 is a side elevation of a detached portion of the part of a windmill which carries the brake. Fig. 5 is a vertical section, taken at the line 5—5, Fig. 4, looking to the right. Fig. 6 is a side elevation of the brake; o and Fig. 7 is a vertical section, taken at the line 7—7, Fig. 6.

The object of my invention is to make an efficient brake for a solid wheel windmill in which the brake will be applied when the 5 wheel is pulled around out of wind.

When the tank is full of water, or when it is not desired to have the water stand in the pump where it is liable to freeze in cold weather, the mill is ordinarily swung around o and fastened out of wind. It is important at such times that the wheel be prevented from turning so that the wear of the mill will cease and that the water will be allowed to run out of the pump.

5 My invention consists in the parts and combination of parts hereinafter fully described and made the subject matter of the claims.

In the accompanying drawings, A represents the windmill tower; B, the cap of the o tower, securely bolted thereto, and C the turn-table.

D, is the spider of the wind wheel. E, is the wind wheel shaft to which said spider is securely attached in the ordinary manner.

5 F, is an annular rim cast with, or securely attached to, the spider D against which the brake-shoe has a frictional contact to prevent the wheel from revolving.

The brake shoe G is cast with arms, H, in o which are grooves, I, that rest on inclined

lugs, J, one on each slide of that portion of the turn-table, K, which supports the shaft E of the wind wheel. The shoe is of circular form and passes under the wind wheel shaft, and when applied it slides up on the inclined faces 55 of the lugs J till it contacts with the face of the annular rim F on the spider of the wind wheel.

When the force which applies the brake is removed, the weight of the brake causes it to 60 slide downwardly on the inclined faces of the lugs which support it, and the brake is removed from its contact with the annular rim F. The brake has an arm, L, to which the lever, M, is pivoted and by which the brake is 65 applied as above described. The lever M is pivoted to the turn-table or an attachment to the turn-table, N, at O, as clearly shown in Fig. 1 of the drawings. The long arm of the lever projects toward the center of the turn-table, and the rod, P, by which the wind wheel is pulled out of wind, passes through the long end of the lever M, as clearly shown in Figs. 1 and 3. I place also on the rod P an adjustable block, R, which is too large to pass 70 through the hole in the end of the brake-lever M. When the rod is pulled down to turn the wind wheel out of wind, this adjustable block is so adjusted on the rod that just before the wheel is completely turned out of wind, the 80 block strikes the brake-lever and applies the brake, thus stopping the revolution of the wheel when the wheel is fastened out of wind.

The rod P is pivotally attached to one end of the lever, S, which has its bearing on the 85 top of the windmill, as clearly shown in Fig. 1. There is also attached to this lever, a rod, T, which connects with and operates a weighted lever, U. When the rod P is pulled down and thereby vibrating the lever S on its bearings, the rod T raises the long end of the weighted lever U which is pivoted to the turn-table and connected with the tail-vane by a link connection at V in such manner as to turn the turn-table and swing the wind wheel 90 around out of wind.

I do not claim in this application any novelty in the construction or arrangement of the weighted lever or its connection with the turn-table and tail-vane for swinging the 95 100

wind wheel out of wind, or for bringing it back into wind when desired. Neither do I claim to be the first to apply a brake to the spider of the wind wheel, but

5 What I do claim, and desire to secure by Letters Patent, is—

1. In a windmill, a brake having bearings adapted to rest upon lugs or flanges supported on the turn-table; flanges or lugs supported 10 on the turn-table on which the brake has its bearings; a lever pivotally attached to said brake, pivoted on the turn-table and adapted to be connected with the rod by which the wind wheel is thrown out of wind; and a frictional bearing surface connected rigidly to the 15 wind wheel shaft whereby the brake is operated by the rod, and sliding on the lugs or

flanges makes a frictional contact with the attachment of the wind wheel shaft, as specified.

2. The rod with which the wind wheel is thrown out of wind; a stop on the rod adapted to operate the brake-lever; a brake-lever pivoted to the turn-table and connected with the rod and with the brake-shoe; a brake-shoe having bearings adapted to slide upon lugs 25 or flanges; lugs or flanges attached to the turn-table, having inclined bearing surfaces which support the brake-shoe; and a bearing rigidly connected with the wind wheel shaft, substantially as specified.

JOHN H. MILLER.
